UNITED STATES PATENT OFFICE.

CHARLES W. TAYLOR, OF SALT LAKE CITY, UTAH.

DESIGN FOR A SOUND AMPLIFIER.

Application filed April 27, 1925. Serial No. 13,224. Term of patent 7 years.

To all whom it may concern:

Be it known that I, CHARLES W. TAYLOR, a citizen of the United States, residing in Salt Lake City, county of Salt Lake, and State of Utah, have invented a new, original, and ornamental Design for a Sound Amplifier, of which the following is a specification, reference being had to the accompanying drawing, forming part thereof.

The figure is an elevation of a sound amplifier, showing my new design.

I claim:

The ornamental design for a sound amplifier, as shown.

CHARLES W. TAYLOR.
